INTERCEPTOR CHOKE

John R. Wiegand, North Valley Stream, N.Y.

Application March 18, 1955, Serial No. 495,135

4 Claims. (Cl. 336—155)

This invention relates to new and useful improvements in electrical chokes.

This application is a continuation-in-part of my pending application 449,838, filed August 16, 1954, now Patent 2,798,987.

Electrical chokes find numerous applications in electrical and electronic equipment wherein they function as frequency discriminative attenuators and the like. Usually a choke comprises a laminated magnetic core having a coil of conductive wire wound thereon. Electrical impulses to be affected by the choke are transmitted through the coil. If the impulses are of the appropriate frequency relatively little attenuation is encountered. However, impulses of other frequencies are attenuated to a greater degree.

The principal object of the invention is to provide an interceptor choke which is more frequency discriminative than existing chokes, but which may be constructed of the same materials as the latter.

Another object of the invention is to construct the choke in such manner that the same effects a damping action on noise superimposed on the impulses transmitted through the coil.

A further object of the invention is to construct the choke in such manner that a flatter frequency response is exhibited and a greater frequency range provided than is possible with prior art chokes utilizing the same materials.

Still another object of the invention is to provide an interceptor choke which provides for a large increase in the storage factor of the coil with a noticeable decrease in charge and discharge time.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is an isometric view of the choke of the invention encased in a plastic housing.

Fig. 2 is a side elevational view of the choke with the housing removed.

Fig. 3 is an enlarged isometric view of the choke with the housing removed and with only the first few windings of the core in place.

Fig. 4 is a perspective elevational view of a form on which the coil and the core are wound.

Fig. 5 is a diagrammatic illustration of the coil with a single core section wound thereon.

Fig. 6 is a diagrammatic illustration of a same system utilizing the choke.

Fig. 7 is a graph illustrating the characteristics of a 10,000 cycle interceptor choke.

Fig. 8 is a graph illustrating the relative response characteristics of a choke according to the invention and another choke.

Referring to Fig. 1 the choke of the invention is encased in a plastic housing 10 from which a pair of conductive leads 11 project. Interiorly of housing 10 the choke includes a form 12, an annular coil 13 and a wire core 14 wound on the form (see Figs. 2-5). Form 12 includes a pair of substantially square side plates 15 separated by a centrally located, square tube 16. Form 12 is constructed of any suitable insulating material. Each of side plates 15 is provided with corner extensions 17 which extend diagonally outward from the four corners and are wider at their outer than at their inner ends.

As best shown in Fig. 3 the leads 11 which project from the housing 10 in Fig. 1 comprise a pair of conductive rods each having a widened inner end folded about one of the extensions 17 as at 18. Coil 13 is wound on the tube 16 between the side plates 15 and its ends are soldered or otherwise secured to the folded portions 18 of the leads as at 20.

The core 14 comprises magnetic wire wound on the form 12 as best shown in Figs. 2, 3 and 5. The wire may be .003 in. diameter 50% nickel-iron alloy wire. Referring to Fig. 2 the core 14 is wound in four sections 14', each encompassing adjacent corner extensions 17 of the side plates 15. Each of the four sections 14' is wound as shown in Fig. 3. The winding is begun within the tube 16, extends out of the tube as at "A," passes adjacent one side edge of a corner extension 17 of the near side plate 15, crosses the coil 13 to the far side plate where it passes adjacent the opposite side edge of aligned corner extension 17. Thence the winding extends through the tube 16 and out as at "B." Loop B passes adjacent the opposite edge of the corner extension 17 of the near side plate to that engaged by loop A, and traverses diagonally across the latter loop at 30 in crossing the coil 13 to the far side plate. Loop B then extends through tube 16 and emerges as loop C identical with loop A, etc.

It will be seen, therefore, that as shown diagrammatically in Fig. 5 the several loops of each core section 14' traverse the central opening in the coil in parallelism 40 interiorly of the latter at 31, but traverse the coil at substantially right angles to one another exteriorly of the coil at 30. When each section of the core has been provided with the requisite number of loops, the next section is begun until all four sections 14' are wound to make 45 up the complete core 14.

When the core is completely wound as shown in Figs. 2 and 3, the several core sections are arranged in a balanced four-leaf clover pattern on each side of each of plates 15. Each pattern has four elongated lobes whose long axes lie along diagonals of the plates, with the long axis of each lobe disposed perpendicular to the long axes of the two lobes adjacent to it. The strands of the core are disposed in substantial parallelism with each other within the tube. The strands of each core section cross 55 each other between opposed corner extensions 17 of the plates 15 on the outside of the coil 13.

A frequency response curve for a nominal 10,000 cycles per second interceptor choke is shown in Fig. 7. As illustrated, the response characteristic is such that the curve 60 is extremely flat up to 4,000 cycles per second, rises, relatively gradually up to about 8,000 cycles per second and then very sharply to 10,000 cycles.

Referring to Fig. 8, frequency response curves are shown for two chokes. Curve I shows the response for 65 a choke having a four section magnetic core 14 wound on a coil 13 as shown in Fig. 2. Curve II shows the response for a choke having a coil with exactly the same number of turns and shape as the other coil; but the core of the second choke is an ordinary flat laminated rectangular member on which the coil is wound. The inductance of both coils is four henries and the D.C. resistance of both

coils is 1400 ohms. Both chokes have a 50-50 nickel-iron content in the magnetic cores and have the same weight.

As shown in Fig. 8, curve II rises gradually to a first peak at 6,000 cycles and to a second peak at about 12,000 cycles. Neither peak is sharp or well defined. The curve I for the choke of the present invention, however, does not begin to rise appreciably until about 9,000 cycles per second and peaks sharply at 18,000 cycles per second. Obviously the choke of the invention is much more frequency discriminative and efficient and is ideally adapted for passing an extremely narrow band of frequencies.

A simple example of the manner in which the choke of the invention is useful is illustrated diagrammatically in Fig. 6. As shown, a choke 21 is connected in a series circuit with a resistor 23, coil 28 of a relay 27 and a condenser 24. A microphone 25 and a battery 22 are connected in shunt across the resistor. Relay 27 may, for example, have its contacts 29 connected with circuit means M for opening the doors of a garage on energization of the relay. In order to effect energization of the relay, the automobile using the garage is provided with a whistle or the like which utilizes the peaking frequency of the choke. Normally the relay coil would be held deenergized by the relatively high attenuation effected in choke 21. However, on sounding of the whistle of the appropriate frequency an impulse is generated by microphone 25 which energizes the relay coil causing contacts 29 to close.

The choke of the invention may be used in many other environments, for example, hearing aids, computers, etc.

At this point it is deemed wise to point out that the choke has been found to effect a damping action which severely attenuates noise frequencies superimposed on the impulses applied to the choke when these frequencies differ from the optimum frequency response range of the choke. Thus, the choke of the invention improves the condition of the impulses applied to it.

It will also be seen that the crossings of the core as shown provide for a large increase in the storage factor (Q) of the coil with a very noticeable decrease in charge and discharge time, making it ideal for pulse work. Further, by changing the diameter of the core wire and the amount in relation to the copper coil, the maximum Q or storage factor can be adjusted to any desired frequency. Such flexibility of changing or adjustment is very difficult with the ordinary laminated choke which can never reach such a high storage factor on a desired frequency.

While I have illustrated and described the preferred embodiment of my invention, it is to be understood that I do not limit myself to the precise construction herein disclosed and that various changes and modifications may be made within the scope of the invention as defined in the appended claims.

Having thus described my invention, what I claim as new, and desire to secure by United States Letters Patent is:

1. An interceptor choke, comprising an insulation form having square side plates and a centrally disposed tube extending between the plates, a single coil wound around said tube between said side plates, said coil having two terminals for connection to an external circuit, and a core 10 of magnetic wire having strands wound about the coil, extending through the tube and over edges of the side plates, said core being wound in four similar looped sections, the several sections being arranged on each plate 15 in a balanced clover leaf pattern with four elongated lobes having their long axes disposed on diagonals of the plates, the long axis of each lobe being disposed perpendicular to the long axes of the adjacent lobes.
2. An interceptor choke according to claim 1, wherein said strands are disposed in substantial parallelism with 20 each other within the tube.
3. An interceptor choke according to claim 2, wherein each plate is provided with a diagonally extending corner extension, the strands of each section crossing each other 25 between opposed corner extensions of the two plates on the outside of the coil.
4. An interceptor choke according to claim 3, further comprising a pair of conductive rods having ends respectively folded around two extensions of the plates, the two 30 ends of the coils being electrically connected to the respective ends of the rods.
